UNITED STATES PATENT OFFICE

152,615

DESIGN FOR A WEATHER VANE

Otis D. Harbert, Covina, Calif.

Application November 13, 1946, Serial No. 134,764

Term of patent 14 years

(Cl. D52—9)

To all whom it may concern:

Be it known that I, Otis D. Harbert, a citizen of the United States, residing at Covina, in the county of Los Angeles and State of California, have invented a new, original and ornamental Design for a Weather Vane, of which the following is a specification, reference being had to the accompanying drawing, forming part thereof.

Fig. 1 is a perspective view of a weather vane, showing my new design.

Fig. 2 is a front view in elevation.

The essential features of my design reside in the portion shown in full lines.

I claim:

The ornamental design for a weather vane, substantially as shown and described.

OTIS D. HARBERT.
